AXEL G. BERGMAN, OF NEW YORK, N. Y., ASSIGNOR TO ORDNANCE ENGINEERING CORPORATION, OF NEW YORK, N. Y., A CORPORATION OF NEW JERSEY.

HAND-GRENADE.

1,315,592.

Specification of Letters Patent. Patented Sept. 9, 1919.

Application filed June 1, 1917. Serial No. 172,244.

To all whom it may concern:

Be it known that I, AXEL G. BERGMAN, a subject of the King of Sweden, residing in the borough of Manhattan, city, county, and State of New York, have invented certain new and useful Improvements in Hand-Grenades, of which the following is a specification.

This invention relates to hand grenades and aims to provide certain improvements therein.

Hand grenades as heretofore constructed have usually operated either by a time fuse or upon impact. Both constructions have been open to various disadvantages, such as uncertainty of firing, excessive danger in use, complication of structure, etc.

The object of the present invention is to provide a grenade in which these disadvantages are avoided. To this end I have provided a grenade, the firing element of which operates through the inertia of a fly wheel or its equivalent. In the preferred construction such a wheel is mounted within the grenade body and is held fixedly with relation to the body until the grenade is thrown. In the act of throwing, a circular or turning movement is imparted to the grenade body, including the fly wheel, and as soon as the grenade leaves the hand the safety device is displaced, with the result that the fly wheel and body rotate substantially at the same rates of speed, until the grenade reaches the ground or some other point of rest, whereupon the fly wheel continues its rotation, with the effect that the firing means is operated. The invention includes other features of improvement which will be hereinafter more fully described.

Referring to the drawings illustrating one form of the invention,—

Figure 1 is a sectional view on the line 1—1, Fig. 2;

Fig. 2 is a similar view taken at right angles to Fig. 1.

Referring to the drawings, let A indicate the casing of the grenade, which is shown as divided into two explosive compartments B, C, and a middle compartment D which is designed to contain the fly wheel or inertia wheel E. The latter is mounted upon an axle F which preferably extends through all three compartments, as shown. Preferably, the axle is screw-threaded at each end and serves to unite all of the parts of the

body together. The fly wheel is preferably provided with a groove G having a protuberance or protuberances H and I. The device is shown as provided with a spring J which may be fastened at K to the periphery of the body or casing, its free end normally lying in the groove G. Near its end it may be bent as shown at L, so that its bent portion lies normally between the protuberances H and I, the construction thus constituting a frictional catch or holding device which imposes a frictional resistance upon the rotation of the fly wheel, this frictional resistance being variable by proportioning the strength of the spring, or in any other suitable manner.

I have shown the fly wheel as provided with a recess M which is adapted to normally receive a safety pin O, the latter being provided with a spring P which upon restraint would eject the pin from the slot and from the body or casing. Normally, the pin is held in safety position by a safety device such as the cotter pin Q, best shown in Fig. 2, which passes through lugs R and S formed in the top of the casing. The lugs R and S are preferably formed to constitute a notch or finger-hold T on one side of the device, and preferably with a smooth wall U on the opposite side.

The body portion may be provided with one or more bores V and W through which are adapted to be inserted frictional firing devices such as X X having portions extending downwardly into the casing so as to be struck or rubbed by a frictional surface Y which may advantageously be mounted upon a spring mounting such as Z. The spring mounting may consist of a springy material such as sponge rubber or any other suitable material. It is preferable that the firing devices X shall be so constituted that they will not ignite by friction unless accompanied by a chemical reaction such, for instance, as is present in the ordinary safety match and its striking surface. I have shown two detonators a and b, which are inserted in the casing through proper apertures, and which are connected with the space near the firing devices by powder trains or plugs c and d.

In operation the grenade is grasped with one of the fingers, such as the forefinger, in the recess T, whereupon the safety cotter pin Q is withdrawn, the finger holding the safety pin O against the tension of its spring

P in the recess M. The grenade is then thrown, and during the act of throwing it is given a sharp turn or twist so that the grenade rotates more or less rapidly in its flight 5 through the air. There is no particular skill required in this, since it is very difficult to throw the grenade without twisting it, so that the natural motion imparted to the grenade is availed of. Before the safety pin O 10 has left its recess and unlocked the wheel, the twisting motion is imparted to the wheel, so that the grenade flies through the air with the casing and wheel both rotating, but without relative movement. If there is any 15 tendency to relative movement it is checked by the friction spring J. As soon as the grenade reaches its mark, however, and the rotation of the casing is checked, the inertia of the wheel is sufficient to overcome the 20 frictional resistance of the spring and the wheel then rotates relatively to the casing. This relative rotation brings the striking surface Y into contact with the firing devices X, igniting the same, the flames then 25 igniting the powder plugs c, d, and in turn the detonators, whereupon the explosive is fired.

It is preferable that the inertia wheel E 30 rotate with as little friction as possible, and any anti-friction device may be used to promote this. In the construction I have shown a brass bushing e for the wheel which has small contact surfaces f bearing on the axle or shaft F, and also small contact 35 surfaces g which bear against the plates h, i which constitute the separating walls between the several compartments of the casing.

It will be observed that accidental explosion 40 is practically prevented, not only on account of the safety pin O and connected mechanism, but also on account of the fact that to fire the device a distinct relative rotative movement between the fly wheel and the casing is necessary, which movement is practically impossible to occur in falling or dropping, or in any other way than by direct and intentional throwing. It will also be observed that there is no complicated or 45 delicate mechanism involved which is expensive to construct or liable to get out of order. Furthermore, there is no weight which is to be dislodged by impact, and no finely poised firing parts. It will also be observed that 50 since the device does not operate by impact, but merely by stoppage of the rotation of the casing, the degree of shock which it receives is immaterial. Thus, the device will explode when it falls in mud or water, or other 55 medium too soft to operate an impact firing device. Moreover, the device is extremely cheap and simple to construct, and has no complicated parts or delicate mechanism.

While I have described the device with 60 relation to a hand grenade, it will be under-

stood that it may be used in connection with other projectiles. While I have shown and described the inertia member as a wheel, it will be understood that by this term I mean to include other inertia devices which operate around a substantially fixed axis. 70

It will be understood that I have shown one form of the device merely as an illustration, and that the construction may be widely varied without departing from the 75 invention.

What I claim is:

1. A hand grenade having a firing mechanism comprising an inertia wheel which is free to turn at any point in the flight of the 80 grenade, and is brought into operation upon impact of the latter.

2. A hand grenade having a firing mechanism including an inertia wheel which is free to turn at any point during the flight 85 of the grenade, and is brought into operation upon impact of the latter, and means for retarding rotation of said wheel.

3. A hand grenade having a firing mechanism including an inertia wheel which is free to rotate at any point in the flight 90 of the grenade, and is brought into operation upon impact of the latter, and a manually-controlled safety device which is released instantly as the grenade is thrown. 95

4. A hand grenade having a firing mechanism including an inertia wheel which is free to rotate at any point during the flight of the grenade, and is brought into operation upon impact of the latter, and a 100 manually-controlled safety pin which normally engages the inertia wheel and is released instantly upon throwing the grenade.

5. A hand grenade consisting of a body, and having a firing mechanism including 105 an inertia wheel which is free to turn at any point in the flight of the grenade, a frictional device and an igniting device, one carried by said body and the other by said inertia wheel, and coming into frictional contact 110 with each other when said inertia wheel rotates upon impact of the grenade.

6. A hand grenade comprising a body, and having a firing mechanism including an inertia wheel which is free to rotate at any point 115 in the flight of the grenade, a frictional device carried by the inertia wheel, and an igniting device carried by the body, adapted to be brought into contact with the frictional device upon rotation of said inertia 120 wheel.

7. A hand grenade or the like comprising a casing, an inertia wheel therein, a safety pin engaging the periphery of said inertia wheel, said safety pin being adapted to be 125 dislodged on throwing, a lock for said safety pin, and an igniting device ignited by said wheel.

8. A hand grenade or the like comprising a casing consisting of separate parts, an in- 130

ertia wheel with igniting means, and a shaft for said wheel, said shaft holding the parts of the casing together.

9. A hand grenade having a firing device including an inertia wheel which is free to rotate at any point in the flight of the grenade, and frictional means acting to retard rotation of the inertia wheel and prevent its operating except upon impact of the grenade.

10. A hand grenade or the like having a

firing device comprising an inertia wheel, and a spring frictional device for retarding the wheel.

11. A hand grenade or the like comprising an inertia wheel, said wheel having an uneven surface on a part thereof, and a spring device engaging said uneven surface to normally retard the rotation of said wheel.

In witness whereof I have hereunto signed my name.

AXEL G. BERGMAN.
